UNITED STATES PATENT OFFICE.

REUBEN H. SAYRE, OF NEW MARTINSVILLE, WEST VIRGINIA, ASSIGNOR OF ONE-HALF TO
GEORGE W. KOTZEBUE, OF NEW MARTINSVILLE, WEST VIRGINIA.

FURNACE.

No. 914,814.

Specification of Letters Patent. Patented March 2, 1909.

Application filed May 13, 1908. Serial No. 432,676.

To all whom it may concern:

Be it known that I, REUBEN H. SAYRE, a citizen of the United States, residing at New Martinsville, in the county of Wetzel and State of West Virginia, have invented a new and useful Furnace, of which the following is a specification.

This invention relates to improvements in furnaces, and one object is to provide an ash sifting device to be used in conjunction with the grate bars, so that whenever the grate is operated by the shaking lever, the ashes passing through the grate will be caught upon a sifting screen and the finer ashes separated from the coarser ashes, which latter containing unburned materials may be replaced in the fire-box for further burning. The sifter is removably connected to the shaking lever, so that whenever the grate bars are operated by the lever, the sifter will likewise be operated, and may be readily detached from the lever for withdrawal from the ash pit of the furnace, so that ready access may be had to the sifter for the removal of the cleaned ashes.

The body of the furnace as shown in the drawings is in general similar to that shown in Letters Patent No. 759318, granted to me on May 10, 1904, for hot air furnace.

In the aforesaid patent various parts of the furnace are shown as riveted together. This makes it difficult when it is necessary to replace portions of the furnace that may have become damaged or burned out, and, also, increases the cost of manufacture. In the furnace forming the subject matter of the present invention, the body portions and the end portions of the furnace structure are connected together by ears and bolts, and the end plates or castings are so constructed as to receive the corresponding ends of the body portions in recesses or grooves formed in the said end plates with asbestos or other suitable refractory material forming gas tight joints where the body portions enter the grooves.

The invention will be best understood from a consideration of the following detailed description taken in connection with the accompanying drawings forming a part of this specification, in which drawings,

Figure 1 is a longitudinal section of the furnace. Fig. 2 is a front elevation with parts broken away and in section. Figs. 3, 4, 5 and 6 are detail views.

Similar numerals of reference are employed to indicate corresponding parts throughout the several figures of the drawings.

The main body of the furnace comprises a front plate 1 and a back plate 2 connected by side plates 3 and a crown plate 4, all similar in construction to these parts of the furnace shown in the aforesaid Letters Patent.

Around the edges of the front plate 1 and rear plate 2 there is formed a groove or rabbet 5, into which is seated the corresponding edges of the side and top plates 3 and 4. The grooves 5 are of such width as to receive a packing 6 of asbestos or other refractory material embracing the edges of the plates 3 and 4 and surrounding the ends thereof. Formed at appropriate points on the edges of the front and back plates are ears 7, appropriately spaced, and fast on the side plates 3 and 4 in position to match the ears 7 are angle bars 8 held to the plates 3 and 4 by suitable bolts 9. The holes through the ears 7 and 8 coincide so as to permit the passage of drawing-up bolts 10, by means of which the edges of the plates 3 and 4 are firmly seated in the grooves or rabbets 5 with the asbestos lining 6 packed therein.

Within the space between the front and back plates 1 and 2 is located the fire-box which is appropriately lined with fire-brick 11, and below the fire-brick there is located a suitable grate 12, the structure of which forms no part of the present invention, and, therefore, need not be particularly described. In the specific form shown, the grate bars have downwardly extending fingers 13, all connected to a common strip 14, one end of which is connected to a link 15 extending through the front member of the furnace on the exterior thereof. Suitably pivoted in a bracket 16 fast on the outer face of the front of the furnace is an operating lever 17, the shorter end of which is connected by the link 15 to the bar 14, and thereby to the several grate bars, so that upon a suitable manipulation of the lever 17, the grate bars are all rocked simultaneously.

The front of the furnace is provided with the usual fire-box door 18, and clinker door 19, while the usual ash pit door is omitted, and the bottom of the ash pit is occupied by an ash pan 20, the front 21 of which is made sufficiently expanded to close the ori-

ifice necessary for the introduction of the ash pan, and so prevent the entrance of air at this point. The ash pan 20 is provided at the front end with a suitable handle 22 by means of which it may be withdrawn from the ash pit, and within the body of the ash pan there are folding handles or bails 23, by means of which the ash pan may be conveniently carried to a point of deposit 10 for the ashes. Within the ash pit, above and on each side of the ash pan, are formed ledges 24, and near the front end these ledges carry rollers 25 for the reception of a pan 26, the bottom 27 of which is perforated. 15 The pan near its rear end is provided on the bottom with rollers 28 adapted to travel on the ledges 24.

The front of the casing of the furnace coincident with the space provided for the 20 reception of the pan 26, has an opening 29 for the introduction or removal of the said pan, and at the lower edge of this opening there is formed an outwardly projecting lip 30, to which is hinged a door 31, constituting 25 the lower draft door of the furnace, and at the ends of the lip 30 are formed inclined sides 32, so that the door 31 will lie in an inclined position when closed. This door is provided with the usual hinged flap 33, 30 having its free edge provided with legs 34, so that when the door 31 is in a horizontal position and the flap 33 is pendent, the legs 34 will engage the floor upon which the furnace rests. The lip 30 and door 31 when in 35 the horizontal position constitute a support for the pan 26, so that the latter may be partly withdrawn from the ash pit in a position to be readily accessible with a shovel.

Hinged to a bracket 35 fast on the front of 40 the furnace is a rock lever 36, one end of which is extended through a suitable opening in the lower end of the shaking lever 17, and the other end of which carries a stud 37 adapted to enter a hole or perforation in the 45 handled end 38 of a link 39, pivotally secured at the other end to the front of the sifter pan 26, as indicated at 40.

Let it be assumed that a fire is burning in 50 the fire-box and that it is desired to shake down the fire, then the handle 17 is grasped and oscillated in the usual manner about its pivot support 16. This will cause the simultaneous rocking of all of the grate bars 12, and the ashes thus disturbed will fall 55 through the grate until finally arrested by the pan 26. However, this pan is also reciprocating at the same time the grate bars are being rocked, and the finer ashes will find their way through the perforations in the bottom 27 of the pan and fall into the ash pan 20, while the coarser particles of the ashes are retained in the pan 26. When bituminous coal is used in the furnace, more or less coked, but otherwise unburned coal, 60 finds its way into the pan 26 in lumps too

large to pass through the perforations in the bottom 27, and these lumps of coal are valuable for reburning. After the fire has been shaken down, the pan 26 may be withdrawn from the furnace by first unhooking 70 the handle end 38 of the link 39 from engagement with the pin 37 and this handle may be utilized for the purpose of pulling out the pan 26 from the ash pit. When the pan has been pulled sufficiently out from 75 the furnace to be accessible from the outside, it will be supported upon the door 31, which, in the meantime, has been brought to the horizontal position shown in Fig. 1. Now, the operator may, with a suitable 80 shovel, remove the coked material retained by the pan 26 and again deposit the same in the furnace. This coked material is valuable for banking fires at night, as well as being useful on a live fire. 85

The rock lever 36 is located somewhat above the opening for the passage of the pan 26 and the link 39 is normally within an off-set 41 of the opening. In order to close this opening to a sufficient extent to 90 prevent undue draft therethrough, there is provided a slide 42 having a forked end adapted to straddle the link 39 when connected to the rocker arm 36. When it is desired to remove the pan, the slide 42 is 95 moved to one side out of the path of the link 39, and the latter may then be removed from the pin 37 and permitted to drop down into the main opening 29, so as not to interfere with the removal of the pan 26. 100

In the aforesaid Letters Patent there is a portion of the furnace which is there designated as the radiator casing and this casing is shown in Figs. 1 and 3 of the present application at 43. In the aforesaid Letters 105 Patent the lower end of this casing is provided with a rectangular opening connected by a rectangular flanged collar with a similar opening in the lower part of the back wall of the furnace. In the present structure the rectangular collar is omitted and replaced by two flanged cylindrical collars 44, spaced apart and connecting the radiator casing with the lower end of the back wall 2 of the furnace. 110

The asbestos packing is used wherever there is danger of coal gas reaching the air drums of the furnace, and wherever a junction is formed between two metal parts where there may be a leak of gas, an asbestos strip, such as shown at 45 in Fig. 5, may be employed. 115

In the construction of the furnace, the ends 1 and 2, and any other portions requiring solidity are made of cast metal, while the sides 3 and top 4 and the outer linings may all be made of sheet metal, such, for instance, as sheet steel. 125

What is claimed is:—

1. In a furnace, the combination with a 130

rocking grate, of a reciprocating sifting pan below the grate, a shaking lever for the grate, a withdrawing means for the pan fast thereto, and means between the withdrawing means and the shaking lever attachable to and detachable from the said withdrawing means at will without disturbing the connections of the shaking lever with the grate.

10 2. In a furnace, a shaking grate, a shaking lever therefor exterior to the furnace, and connected to the grate, a shifting pan below the grate, a rocking lever carried by the furnace exterior thereto and connected to the shaking lever, and removable connections between the shifting pan and the rocking lever.

15 3. In a furnace, a shaking grate, a shaking lever therefor exterior to the furnace and connected to the grate, an ash-pit door below the grate, the said furnace having openings through its walls, one opening being coincident with the said ash-pit door and the other opening being below the latter, a sifting pan adapted to be inserted in and removed from the furnace through the ash-pit door opening, means for connecting the sifting pan to the shaking lever and disconnecting the same therefrom at will, and an ash-pan insertible in and removable from the furnace through the opening below the ash door opening and constituting a closure for the ash-pit below the ash-pit door when the pan is inserted therein.

4. In a furnace, a shaking grate, a shaking lever therefor exterior to the furnace, a sifting pan adapted to be inserted in and removed from the furnace below the grate, said furnace having superposed openings through its walls below the grate and leading to the ash-pit, a door for the upper one of the said openings movable to form a support for the sifting pan when partially removed from the furnace, a handle for the sifting pan, connecting means between the said handle and the shaking lever attachable to and removable from the sifting pan handle at

will, and an ash-pan insertible in and removable from the furnace through the lower opening and constituting a closure for the corresponding portion of the ash-pit when inserted therein.

55

5. In a furnace, a shaking grate, a shaking lever therefor exterior to the furnace, and connected to the grate, a sifting pan below the grate, a rocking lever carried by the furnace exterior thereto and connected to the shaking lever, and removable connections between the sifting pan and the rocking lever.

60

6. In a furnace, a shaking grate, a shaking lever therefor exterior to the furnace and connected to the grate, a sifting pan below the grate, a rocking lever carried by the furnace exterior thereto and connected to the shaking lever, and removable connections between the sifting pan and the rocking lever, the said removable connections constituting a handle for the manipulation of the sifting pan when disconnected from the rocking lever.

65

7. In a furnace, a shaking grate, a shaking lever therefor, a fixed ledge below the grate, a sifting pan adapted to move on said ledge, connecting means between the shaking lever of the grate and the sifting pan for simultaneous movement of the latter with the grate, and an ash-pan insertible into and removable from the ash-pit below the ledges supporting the sifting pan, the said furnace being provided with an opening through its walls for the insertion and removable of the ash pan.

75

8. In a furnace, a shaking grate, a shaking lever therefor, ledges below the grate, rollers on said ledges near the front end of the furnace, a sifting pan having a previous bottom and adapted to the ledges, and rollers on said pan near the rear end thereof.

80

In testimony that I claim the foregoing as my own, I have hereto affixed my signature in the presence of two witnesses.

REUBEN H. SAYRE.
